UNITED STATES PATENT OFFICE.

HAMMOND CHARLES HASTINGS AND CYRIL JOHN SARJEANT, OF RUGBY, ENGLAND,
ASSIGNORS TO GENERAL ELECTRIC COMPANY, A CORPORATION OF NEW YORK.

PROTECTIVE DEVICE FOR DYNAMO-ELECTRIC MACHINES.

Application filed November 13, 1923, Serial No. 674,584, and in Great Britain December 14, 1922.

This invention relates to protective devices for dynamo electric machines and more particularly to means for automatically changing the calibration of the circuit breaker of a feeder where one or more machines are required to run in parallel and supply current through the circuit breaker. Such an arrangement is particularly applicable to automatic sub-stations where there are no attendants present to alter the calibration of the circuit breaker when one or more of the machines is automatically cut out, or cut into circuit, although the invention is not limited in its application to an automatic sub-station.

The accompanying diagram illustrates one method of carrying out our invention, as applied to a high speed circuit breaker, such for example as is described in the patent of John F. Tittle, No. 1,560,440, dated November 3, 1925.

In the drawing, a circuit breaker 1 is adapted to be connected to a feeder 37. In order to close this breaker, a push button 21 is closed and completes the circuit of an energizing coil 18 for a contactor 38. This closes contacts 19 and 20, the former completing a circuit around the push button, so that on its being released the contactor 38 will remain closed. Contact 20 completes the circuit of a coil 16 of a contactor 42 through a holding coil 3 of the circuit breaker 1, and a contact 40 of a contactor 41. The coil 16 is in parallel with resistance 22. The contact 40 remains closed as long as the circuit breaker 1 is open, as its operating coil 39 is energized through bridging contact 43, which remains closed so long as the main breaker 1 is in its open position.

Although coil 3 is thus energized, the effect of the magnet 2 is not sufficient to close the main circuit breaker.

When the coil 16 of contactor 42 is energized it causes the contact 17 to close thereby energizing the closing coil 11 of the breaker 1. The magnetic core 12 of this coil 11 then attracts a lever 9 pivoted at 45 which moves the contact arm 6 toward the closed position against the action of the

spring 13. Before the contacts 7 and 8 of 50 the main breaker engage, the pole piece 5 of the circuit breaker is brought in contact with the poles of magnet 2. As the arm 6 moves it first closes an auxiliary contact 15 and then opens the contact 43 through link 55 mechanism 14 pivoted at 44. The auxiliary contact 15 short circuits the coil 16 and the resistance 22 thereby connecting the holding coil 3 of the main breaker across the full voltage of the control bus bars 50. The 60 short circuiting of coil 16 causes the contact 17 to open, and thus deenergize the closing coil 11 of the main breaker, thus allowing the lever 9 to assume its normal position and permitting the strain set up in spring 65 13 to operate contact arm 6 to bring contact 7 in engagement with contact 8. Bridging contact 43 when operated through the link mechanism 14 opens the circuit of the coil 39 of the contactor 41 thus allowing the contact 40 to open. When this contact opens it removes the short circuit from the resistance 22 and the main circuit breaker is then held in its closed position 70 by the holding coil 3 which is connected 75 in series with the resistance 22.

The object of first short circuiting the resistance 22 and then removing the short circuit is to obtain better calibration of the circuit breaker if the magnetizing current 80 is first raised above normal and then decreased to the normal. This feature is claimed in an application of John F. Tittle, and Jacob W. McNairy, Serial No. 6,204, filed February 2, 1925, a division of a former 85 application, Serial No. 683,533, filed December 31, 1923, which said applications are assigned to the same assignee as the present application. The calibration of the main breaker with all the resistance 22 in circuit 90 is the lowest calibration required, when only one of the generators 35 or 36 is connected to the bus bar 30 from which the feeder 37 is supplied, and these machines are connected to the bus bar through circuit interrupters 31 and 33 respectively. When both machines 35 and 36 are connected to the bus bar, it is necessary to raise the calibration 95

of the breaker 1 in order to allow the current of both machines to pass through this breaker. Circuit interrupters 31 and 33 are provided with auxiliary contacts 32 and 34 connected in series, and when both these interrupters are closed a circuit for coil 23 of contactor 46 is completed through a bridging contact 29 carried by a contactor 47. Contactor 46 therefore closes, and its contact 26 short circuits resistance 22 to raise the magnetizing current in the operating coil 3 of the breaker 1 to its maximum value. An auxiliary contact 24 on the contactor 46 closes the circuit of the operating coil 25 of the contactor 47 through auxiliary contacts 32 and 34 on the interrupters. The contactor 47 then closes and its contact 27 completes a circuit across a portion of the resistance 22. At the same time an auxiliary contact 28 carried by this contactor completes a circuit around the contact 24 on contactor 46 to form a retaining circuit for the coil 25 and the auxiliary contact 29 opens the circuit of coil 23.

25 The deenergizing of this coil opens contacts 26 and 24 and thereby prevents contactor 47 from being reclosed if opened for any cause, until the contactor 6 has been again closed. The opening of contactor 26 also removes the short circuit across the resistance 22.

30 The amount of resistance short circuited by the contact 27 is sufficient to raise the calibration of the circuit breaker to the correct setting for both machines 35 and 36 to supply power through the breaker.

35 While both machines are running, if it is necessary to disconnect one of them from the feeder for any reason, its interrupter will be opened and the auxiliary contact carried by the interrupter will break the circuit of coil 25 of the contactor 47. When this coil is deenergized contacts 27, 28 and 29, assume their normal positions, the contact 27 removing the short circuit across the section of resistance 22 so that the main breaker will be calibrated to take the load of the machine which is left running. Auxiliary contact 28 when opened breaks the circuit of coil 25 so that it is impossible to reclose contactor 47 before contactor 46 has been closed.

40 The auxiliary contact 29 on contactor 47 completes a circuit for the coil 23 so that when the machines are again to be run in parallel, this coil will again be energized and the calibration of the main breaker will be raised.

45 It is to be understood that the above description is only given by way of example, and that other means may be employed for changing the calibration of the main feeder circuit breaker.

50 It should also be understood that although we have described a particular type of circuit breaker, the principle of our invention

55 may be applied to other types of circuit breakers, and that although we have only illustrated two machines, the invention is not limited to this number, as a greater number may be employed.

79

What we claim as new and desire to secure by Letters Patent of the United States, is,—

1. The combination with an automatic circuit breaker arranged to interrupt a controlled circuit in response to a predetermined value of current, of a calibrating device for varying the value of current at which the circuit breaker automatically interrupts the controlled circuit, a plurality of dynamo electric machines arranged to be connected in the circuit through the said circuit breaker, and means automatically operated in response to the number of said machines included in the said circuit for varying the said calibrating device. 80

85

2. The combination with an automatic circuit breaker of the type having a magnet for holding the breaker closed against the action of means responsive to the current in the controlled circuit tending to render the holding magnet ineffective, of means for varying the energization of the said holding magnet, a plurality of dynamo electric machines arranged to be connected in the circuit through the said breaker, and means automatically operated in response to the number of said machines included in the said circuit for controlling the said varying means. 90

95

3. The combination with an automatic circuit breaker of the type having a magnet for holding the breaker closed against the action of means responsive to the current in the controlled circuit tending to render the holding means ineffective, of a variable resistor for controlling the energization of the said holding magnet, a plurality of dynamo electric machines arranged to be connected in the circuit through the said breaker, and means automatically operated responsive to varying the number of said machines included in the said circuit for temporarily short circuiting the said resistor and then regulating the effective resistance thereof to calibrate the breaker for the change in the number of machines included in the said circuit. 100

105

4. An electrical system comprising a main circuit, interrupting means therefor, a plurality of secondary circuits, connecting means between each secondary circuit and the main circuit and means responsive to the number of connecting means of the secondary circuits in a predetermined condition for controlling the operation of the interrupting means of the main circuit. 110

115

5. The combination with a main circuit, interrupting means therefor, a plurality of secondary circuits, a circuit interrupter between each secondary circuit and the main 120

125

130

circuit, and means for opening the interrupting means of the main circuit in response to a current traversal thereof in excess of a predetermined value, of means responsive to the number of closed circuit interrupters of the secondary circuits for determining the value of the current traversing the main circuit that shall cause the

interrupting means of the main circuit to be opened.

In witness whereof, we have hereunto set our hands this twenty-ninth day of October, 1923.

HAMMOND CHARLES HASTINGS.
CYRIL JOHN SARJEANT.
